FILLER DEVICE FOR EDGE ROLLING MACHINES

John P. McCaslin, Fort Thomas, Ky., assignor to
The Andrews Steel Company, a corporation of
Delaware

Application September 18, 1939, Serial No. 295,438

7 Claims. (Cl. 80—51)

This invention relates to improvements in an edging roll means used in steel mills for rolling hot metal bars for reducing their width, and particularly pertains to the use of adjustable means or insert filler guide bars which are readily attached to and detached from some stationary part adjacent the edging rolls whereby the edging roll means is caused to accommodate the rolling of hot metal bars of different thickness without requiring a change of the edging rolls or a set thereof each time that a hot metal bar of different thickness is to be rolled. The adjustable means adapts the rolls to bars of different thicknesses or the insert filler guide bars are to be changed rather than the edging rolls for the bars of different thicknesses to be rolled.

An edging roll unit comprises a pair or set of vertically disposed rolls spaced apart a desired distance to receive the hot metal bar of indefinite length and roll it to a reduced width. One edging roll is adjustable relatively to the other so that the edging rolls can be set apart from each other any desired distance for reducing the hot metal roll to the desired width. Ordinarily the adjustable edging roll is mounted in a journal support that can be actuated by a screw device or other suitable means for adjusting the edge roll journaled thereon relatively to the other edging roll which is preferably stationary. However, no ready adjustment means have heretofore been found for adapting a single set or pair of edging rolls to accommodate the hot metal bars of different thickness that are to be rolled. The practice in the art has required different sets or pairs of edging rolls for all the different thicknesses of the bars which are to be rolled. There would need to be a separate set or pair of rolls for each different thickness of bars to be rolled. This, of course, is not only expensive in that a large supply of different pairs or sets of rolls are required, but much time is required in changing one set of rolls for another set. The time required for changing the rolls varies from thirty minutes to several hours, depending somewhat on the type of edging roll unit. Because change of rolls has been accepted as the only solution of the problem, the more modern edging units have been constructed to make the rolls as easily changeable as possible. Production, of course, necessarily stops while the roll sets are being changed, and thus speed of change from one set of rolls to another is desired.

The edging rolls of a pair or set are duplicates, each being provided with an annular recess disposed about its peripheral face, leaving an end

flange on each side of the recess. The width of the annular recess is such to the thickness of the bar of metal to be rolled that its marginal edge snugly fits into the recess of one roll and the opposite marginal edge of the bar snugly fits into the recess of the other roll.

It is the aim of this invention to employ edging rolls, having a recess of a width exceeding the maximum thickness of any metal bar that is to be rolled, and employ with said rolls either an adjusting means or a readily attachable and detachable accessory device or devices to reduce the width of the space to the width of the bar to be rolled. The adjusting means is generally typified by a collar or sleeve having an annular flange forming one side wall of an annular groove and adapted to be actuated to and from another side wall of the groove for providing a groove of the desired width. The accessory device is generally typified by two sets (right and left hand sets) of guide or insert metal bars, one set of which is associated with one edging roll and the other set is associated with the other edging roll. Each set of guide or insert bars preferably comprise separate upper and lower bars. While the lower guide or insert bar is, like the upper guide or insert bar, readily attachable and detachable in position in respect to the roll, it can be used in rolling all the metal bars of different width and thus might be a permanent attachment if desired. Its bearing surface exposed to the metal bar being rolled is in alignment with the path of idle rolls or other devices over which the metal bar is fed to and from the edging device.

The cost of the guide or insert bars is not only inconsequential as compared with the edging rolls, but they can be changed in practically no time at all besides being more adapted for convenient handling and keeping in stock. The time and labor required for changing the guide or insert bars is merely that involved in removing one guide bar and substituting another guide bar therefor. With the guide or insert device as an accessory to the edging rolls, one set only of edging rolls is adapted for rolling metal bars of all the different thicknesses desired. With a single set of rolls and substitute guide or insert bars of different sizes, rolling of varying thicknesses of hot metal bars may be done by merely changing the different size guide or insert bars.

For a better understanding of the invention reference may be made to the accompanying drawings in which:

Fig. 1 is a plan view of a bar edging mill embodying the invention;

Fig. 2 is an enlarged vertical cross section on plane of line 2-2 of Fig. 1;

Fig. 3 is a sectional plan, on the scale and on plane of line 3-3 of Fig. 2;

Fig. 4 is a perspective of the two brackets, the lower bar in place and the upper bar being inserted, in association with the right hand roll which is shown by dotted lines;

Fig. 5 is an enlarged detail front elevation of the right hand front bracket;

Fig. 6 is a partial vertical longitudinal section, on a larger scale, on plane of line 6-6 of Fig. 2, showing both rolls;

Fig. 7 is a section similar to Fig. 6, but of one roll only, the roll body being in elevation, and illustrating a modified roll;

Fig. 8 is a similar view to Fig. 7, partly in section and partly in elevation, illustrating a second modified roll;

Fig. 9 is a vertical cross-section similar to that in Fig. 2, illustrating modified bars and brackets therefor;

Fig. 10 is a detail perspective of the modified right hand rear bracket; and

Fig. 11 is a detail perspective of modified right hand upper bars.

Referring specifically to the drawings in which like numerals are used to designate like parts, numeral 1 designates a frame or base on which pedestals 2 and 3 are mounted. Pedestal 2 is usually stationary, whereas pedestal 3 is movably mounted so as to be adjusted to and from the stationary pedestal. The upper part of the pedestal 3 is provided with a journal bearing 4 capped by 4' bolted to the pedestal 3 at 5 to receive a shaft 6 to which is keyed at 7 a sleeve 8 and a beveled gear 9'. The sleeve 8 with upstanding end flanges rotates with the shaft in the bearing 4. The beveled gear 9' is mounted on the shaft in a position to mesh with a complementary bevel gear 10' which is mounted on and keyed to vertical shaft 11. The vertical shaft 11 is journaled in a bearing 12 in bracket 13 attached to pedestal 3. On the vertical shaft 11 is mounted a roll 14' provided on its peripheral face with an annular recess 15 disposed between spaced apart flange portions 16, resulting from the formation of the recess. These flanges 16 may be integrally formed with the roll 14' or be separate parts screw-threaded or otherwise attached to the rolls. The lower end of roll 14' is recessed at 17 to receive the end 18 of a stub shaft, the other end 19, preferably reduced in diameter, of which projects and is fixed in bracket 20 provided on pedestal 3. An anti-friction sleeve 21 is inserted to line the wall of the recess 17 and anti-friction discs 22 are placed in a sub-recess 23 formed in the roll 14' adjacent that end of the stub shaft which fits in the recess 17 of the roll.

The other vertical edging roll 14 is similarly mounted on the pedestal 2 and driven by intermeshing bevel gears 9 and 10, the only essential difference being that pedestal 3 is adapted to be moved by some adjusting device, such as a screw 24 or the like. Leading to and from the edging device are any number of idle rollers 25, or the like, over which a heated bar of metal A is to be conveyed to the edging device for being reduced in width. Thereafter the bar may be fed to other edging rolls of like construction to be further reduced in width after in the meantime having been fed through horizontal rolls for reducing its thickness. In drawing out and roll-

ing the metal bar, it is alternately fed to a set of horizontal and edging rolls.

With an edging device, typified by the above described construction, there is provided a set 5 of left and right upper guide or insert bars 26 and a set of lower guide or insert bars 27 which can be advantageously associated with a single set of vertical rolls to accommodate bars of different thicknesses for rolling.

10 Upper guide bar 26 is of indefinite length suitable for providing a substantial bearing surface 28 on its underside to contact with the upper marginal side of the bar being rolled. One guide or insert bar 26 is supported in position in respect to the roll by means of a bracket 29 attached to the pedestal 2 on one side of roll 14 and a bracket 30 on the other side of roll 14. Bracket 29 has a base portion bolted at 31 to the pedestal 2 or some other stationary part, and a part 32 projecting to receive the ends of guide bars 26 and 27 to which they are attached by bolts 33 and 34 extending through recesses formed in the bracket and the ends of the guide bars 26 and 27. The other guide or insert bar 26 is likewise attached by brackets 29 and 30 in similar disposition to the other vertical roll 14'.

The other ends of the guide bars are supported by the bracket 30 which has a base part 35, reinforced by rib 36, bolted to the pedestal 2 by bolts 37. The bracket projects to form forked arms 38 and 39. Upper arm 38 is recessed at 40 and 41 to receive the respective fins 42 and 43 on the upper guide bars 26. The upper guide bar 26 is slid into place with the fins 42 and 43 on the 35 guide bar interfitting with corresponding grooves 40 and 41 on the brackets. Abutment 44 may be advantageously provided on the upper guide bar 26 to limit insertion of the bar when the recess in its opposite end bar is in alignment with the recess in the bracket for insertion of bolt 33 which holds the upper guide bar in its assembled position with respect to the edging roll and attached to the brackets. The bolt 33 is not necessary but is merely representative of any positive means 40 for securing the guide bar in its assembled position.

The lower arm is provided with similar grooves 45 and 46 to receive respective fins 47 and 48 on the lower guide bars 27. The fins prevent lateral 50 displacement and the bolts hold the guide bar in position. Bolt 34 is not necessary but is representative of any positive means for securing the guide bar in its assembled position.

It is apparent from the above described construction that the upper guide bars or both are each readily inserted and removed, thereby permitting the same rolls to be used for rolling metal bars of different thickness. Upper guide bars of different thickness through the cross-sections 60 that fit within the recess of the edging roll are employed and inserted to accommodate rolling bars of different thickness.

The annular flanges 16 forming the side walls of annular recess 15 in the periphery of the vertical roll are either integral with or separate members attached to the roll. If in the form of separate members, they can be advantageously screw-threadedly connected with the rolls so as to be adjusted to the proper width for providing a recess therebetween of the desired width. The modified construction in Fig. 7 typifies an edging roll unit comprising a pair of vertical rolls, each being provided with a collar 49 screw-threadedly 70 attached to the roll 14 at 50 to secure an anti-

friction bearing between the collar 49 and a shoulder 51 on the roll. The anti-friction bearing comprises spaced apart rings 52 and 53 providing a raceway for the balls 54 which are interposed therebetween. The seat of shoulder 51 is in alignment with the top surface of guide bar 26 which is adjacent the roll, thereby permitting ring 53 to seat on the shoulder and the top surface of the guide bar. To prevent the ring from rotating with the roll, a downwardly extending lip 55 may be provided to abut the front edge of the guide bar 26. A duplicate construction is provided on the bottom end of the roll 14 for cooperation with the lower guide bar 27.

The modified construction in Fig. 8 typifies an edging roll unit having the vertical rolls each provided with an adjustable collar or flange in relation to a stationary collar or flange on the roll. The vertical roll has a reduced neck screw-threaded at 56 to receive nut 57 and a further reduced neck screw threaded at 58 to receive a lock member 59 fastened to the roll by set screw 60. Nut 57 is an inverted-cup-shaped member with the bottom rim flange 61 forming a side wall of an annular groove opposite to flange 16, integral with the roll, which forms the other side wall. Lock member 59 is of similar shape with its bottom rim embracing the upper part of nut 57 and carrying set screws 62 to engage in respective vertical grooves or recesses 63 in the outer wall of nut 57. As the nut member 59 is screwed down or up on the threaded neck of the roll, the wall of the groove or recess is moved to or from the stationary flange or wall, thereby varying the width of the recess to the thickness of the metal bar A that is to be rolled.

The modification in Figs. 9, 10 and 11 consists in providing front upper and lower guide bar sections 64 and 65, respectively, and rear upper and lower guide bar sections 66 and 67, respectively, a set of these being provided for each vertical roll. Rear bracket 68 is similar to that in Fig. 5, but the front bracket 69 is elongated so that it acts as a splice for the bar sections of each pair. Holes 70 and 71 are provided to receive bolts 72 and 73 which respectively engage the recesses 74 and 75 in the bar sections. This front bracket 69 has ribs 76 and 77, respectively engaging in recesses 78 and 79 formed in the side faces of the adjacent ends of the bar sections, thereby preventing the bars from springing out of place. The bolts 72 and 73 are merely used as additional precautions for holding the bar sections in assembled position in the brackets. They could be omitted if desired. Each set of bar sections are flared at both front and rear, thereby permitting the metal bars that are to be rolled being fed to the rolls in either direction.

I claim:

1. In a machine, for rolling a metal bar, comprising spaced apart rolls between which the metal bar is passed, each of said rolls having an annular recess formed therein, guide means between the side walls and within the recess for regulating the effective width of said recess and providing the top and bottom bearing surfaces, said guide means comprising a member provided with a surface over which the metal bar is passed, and a second member provided with a surface vertically spaced from the surface of the first member, one member being attachable and detachable in position.

2. An edging machine for rolling a metal bar comprising spaced apart edging rolls between which the metal bar is fed, each of said rolls having an annular recess formed therein, guide means between the side walls and within the recess for regulating the effective width of said recess and providing the top and bottom bearing surfaces, said guide means comprising a member provided with a bearing surface over which the metal bar is supported while being fed between the rolls, a second member, complementary with the first member also provided with a bearing surface for the opposite side of the metal bar, and means for supporting the second member in spaced relation to the first member.

3. An edging machine for rolling a metal bar comprising spaced apart edging rolls between which the metal bar is fed, each of the edging rolls having an annular recess formed in its periphery, and a readily attachable and detachable device associated within the recess and between the side walls thereof for providing top and bottom bearing surfaces.

4. An edging machine for rolling a metal bar comprising spaced apart edging rolls between which the metal bar is fed, each of the edging rolls having an annular recess formed therein between spaced apart annular flange portions, a member inserted in the recess against one of the annular flanges to provide one bearing surface for the bar which is being rolled, a second member inserted in the recess against the other annular flange to provide another bearing surface, spaced from the bearing surface on the other member, for the bar being rolled, and means for readily attaching one of the members in position.

5. A guide device for use within annular recesses of rolls in edging machines for rolling metal bars comprising an elongated bar adapted to seat against side walls of the recess and provided with a surface for bearing against the metal bar being rolled and means whereby said bar may be readily attached to and detached from within the recess in the rolls of the edging machine, without dismantling said rolls, to vertically space said bar from a cooperating bearing surface.

6. A guide device for use within annular recesses of rolls in edging machines for rolling metal bars comprising a set of right and left elongated bars adapted to seat against the side walls of the recess, each provided with a surface for bearing against the metal bar being rolled and means whereby the set of bars may be readily attached to and detached from within the recess in the rolls, without dismantling said rolls, to vertically space said bar from a cooperating bearing surface provided within the recess.

7. A guide device for use within annular recesses of rolls in edging machines for rolling metal bars comprising two sets of upper and lower elongated bars adapted to seat within a recess and against the side walls thereof formed in the rolls, each set having opposed bearing surfaces between which a metal bar is adapted to be fed, and means whereby a bar of each set may be readily attached to and detached from within the recess in the rolls, without dismantling said rolls.

JOHN P. McCASLIN,
